UNITED STATES PATENT OFFICE.

ADOLPH GARMISE, OF NEW YORK, N. Y., ASSIGNEE TO SUSPENSION BED SPRING MANUFACTURING CO., OF NEW YORK, N. Y., A CORPORATION OF NEW YORK.

SPRING FOR BEDS, COUCHES, AND THE LIKE.

1,070,678.

Specification of Letters Patent. Patented Aug. 19, 1913.

Application filed January 14, 1913. Serial No. 741,988.

To all whom it may concern:

Be it known that I, ADOLPH GARMISE, a citizen of the United States of America, and a resident of New York, county and State of 5 New York, have invented certain new and useful Improvements in Springs for Beds, Couches, and the Like, of which the following is a specification.

This invention has reference to improvements in springs for beds, couches, sofas, sofa-beds and the like.

It is the special purpose of my invention to produce springs for beds and the like which are provided with means for preventing sagging. The middle portion of a bed spring yields, settles or sinks during continued use and even very strong springs get deformed and distorted in the course of time. At the same time these means for preventing 10 the sagging of the spring should be elastic to a certain degree so as to prevent the spring from becoming rather rigid. To attain this desirable purpose the corner supports of the spring form upward extensions 15 from which the elastic means for preventing the sagging are suspended. These means are secured with their middle portions to the middle side portions of the spring. In this manner the means for preventing the 20 sagging are entirely out of the way when the spring is in use. Additional means are provided on the lower surface of the middle portion of the spring for strengthening this portion so that it will support heavy weights 25 without becoming deformed in the course of time.

By simplicity of construction the cost of production has been kept low. Various details of construction have also been improved with a view of attaining the above desirable objects, and it has been sought to produce an article of neat appearance, all as will be fully described hereinafter with reference to the accompanying drawing in which:

Figure 1 represents in side elevation an improved spring for beds, couches and the like which embodies in desirable form the present improvements. Fig. 2 is a top plan view of the middle edge portion of the spring. Fig. 3 is a cross section on an enlarged scale on line 3—3 of Fig. 1. Fig. 4 represents in plan view braces for supporting the middle portion of the spring, and

Fig. 5 illustrates a modification in the connection of certain parts.

Similar characters of reference denote like parts in all the figures.

In the drawing *a* represents the bed spring proper composed usually of a fabric woven of coiled spiral wire. The spring has enlarged, strengthened edge portions *a'*. It is mounted in substantial frame work comprising strong side bars, rods or pipes *b* which are each secured in two corner supports *c*. These corner supports are connected by angular cross braces *d*. The spring is mounted on these side braces *d*. If desired coiled cylindrical springs *e* may be interposed between the spring proper and the top portion of the angular braces *d* as shown in Fig. 1. The described parts constitute the usual elements of a bed spring.

In order to prevent the sagging of the spring I have provided suspended cables *f* for strengthening and supporting the middle portion of the spring. For the purpose of rendering it possible to suspend the cables, each corner support has an upward extension *c'* which is cast integral with the support as shown in Fig. 1. These extensions *c'* of the corner supports thus are an essential element in the present construction of bed springs. The cables *f* of which two are provided one each provided two corner supports, are secured to the top portion of said supports and extend along the sides of the spring. The middle portion of each cable is permanently secured to the middle portion of the strengthened edge *a'* of the spring as shown in Fig. 1. The cables are preferably made of somewhat elastic material so as to yield to a certain extent. In most instances a woven wire cable is employed of similar wire as the wire of which the spring proper is composed. For securing the central portion of the cable to the reinforced central edge portion of the spring, rivets, bolts, and other suitable means may be used, I prefer however to use the holder shown on an enlarged scale in Fig. 3. This holder consists of a nearly closed metal ring *g* to which a screw *h* is attached having around its upper portion a coiled spring *i* and a nut *j* on its threaded portion. The metal ring *g* is conveniently placed around the cable and the screw passes through the reinforced portion *a* of the

spring while the nut tightens the screw, the cable, and the reinforced portion a^1 of the spring permanently together.

To further strengthen the middle portion 5 of the spring braces k , l , are provided on the lower surface of the central portion of the spring. These braces cross each other in the center as shown in detail in Fig. 4 and have holes k^1 , l^1 , at their ends so arranged that 10 they may be secured by the screws h , h which connect the cable and the spring.

Fig. 5 of the drawing illustrates a slight modification of the connection between the cable and the reinforced edge portion of the 15 spring. Instead of connecting the cable directly to the edge portion of the spring short elastic pieces a^2 are provided between the cable and the edge portion while the construction otherwise remains the same as 20 hereinbefore described.

In the described manner I have produced a novel bed spring embodying means for the prevention of sagging under heavy 25 weights and the spring is not deformed during continued use.

I claim as my invention:

1. A spring for beds, couches and the like, comprising side supports, corner supports thereon having each an integral vertical portion, angular cross braces connecting the 30 said corner supports, a wire spring with

strengthened longitudinal side edges supported in the cross braces, two woven elastic wire cables suspended one each from two opposite top ends of the vertical extensions 35 of the corner supports, holders surrounding the middle cable portions with means thereon to secure them to the middle side edge portions of the spring, and cross braces on the lower surface of the middle spring 40 portion attached with their ends to the securing means of said holders.

2. In a spring for beds, couches and the like, corner supports having each an integral vertical portion extending beyond the 45 spring, two woven elastic wire cables suspended one each from two opposite top ends of said extensions of the corner supports, holders surrounding the middle cable portions, a screw bolt with spring on each 50 holder for connecting the middle cable portion to the side edge of the spring, and cross braces on the lower surface of the middle spring portion secured with their ends to said screw bolts of the holders. 55

Signed at New York, N. Y., this 10th day of January, 1913.

ADOLPH GARMISE.
